UNITED STATES PATENT OFFICE.

OLIVER GRUNDON LAW, OF FINDLAY, OHIO.

DESIGN FOR A SCHOOL WASTE-BAG.

SPECIFICATION forming part of Design No. 30,459, dated April 4, 1899.

Application filed February 23, 1899. Serial No. 706,590. Term of patent 3½ years.

To all whom it may concern:

Be it known that I, OLIVER GRUNDON LAW, a citizen of the United States, and a resident of Findlay, in the county of Hancock and State of Ohio, have invented and produced a new and original Design for School Waste-Bags, of which the following is a specification.

My design is illustrated in the accompanying drawings, forming part of this specification, in which—

Figure 1 is a front view, Fig. 2 is a rear view, and Fig. 3 is a longitudinal section, of a school waste-bag embodying my new and original design.

15 As shown in the drawings, the leading or

material features of my design consist of the body or bag portion, of rectangular shape, and the projecting flap or apron, likewise of rectangular shape, upon the face of which are arranged a series of pockets and an overlapping flap or flaps, all substantially as shown.

Having thus described my invention, what I claim as new, and desire to secure by Letters Patent, is—

The design for a school waste-bag, substantially as herein shown and described.

OLIVER GRUNDON LAW.
